Clarence A. O'Brien

Attorney

UNITED STATES PATENT OFFICE

2,034,314

SHOE LAST HOLDER

Samuel Samuel, Worcester, Mass.

Application December 3, 1934, Serial No. 755,798

3 Claims. (Cl. 12—128.6)

The present invention relates to the art of stretching shoes and has for its prime object to provide means for holding the last which stretches the toe portion of the shoe against distortion and maintaining the heel portion of the shoe in proper shape and formation for comfort.

Another object of the invention resides in the provision of means of this nature which is simple in construction, inexpensive to manufacture, easy to adjust, thoroughly efficient and reliable in use and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawing:

20 Figure 1 is a side elevation of a shoe showing a last and my improved holder in place, a portion of the side of the shoe being broken away.

Figure 2 is a vertical longitudinal section through my holder.

25 Figure 3 is a bottom plan view of one section thereof.

Figure 4 is a rear elevation of said section.

Figure 5 is a rear elevation of the other section.

Figure 6 is a top plan view of said other section.

30 Referring to the drawing in detail it will be seen that the numeral 5 denotes a stretcher last of conventional construction operated in the usual manner by the screw threaded bar 6 and handle 7. This last includes a rear portion having a threaded hole therein through which the threaded part of the bar 6 passes and a front portion which is adjusted by turning movement of the rod to cause said front portion to stretch 35 the toe portion of the shoe. Such lasts are used in stretching the front or toe portion of a shoe but frequently will slip backwardly and have been found to be unsatisfactory.

35 Numeral 8 denotes a cross member mostly used as a handle from which projects a U-shaped frame comprising a bight portion 9 and a pair of spaced parallel co-extensive legs 10, the ends of which are curved downwardly and merge into blades 11 shaped to conform with the conventional heel of a shoe. The bar 6 passes between the legs 10 so that the parts of the device will not interfere with turning movement of the bar. Numeral 12 denotes a plate having a threaded opening 14. Depending from the plate are blades 50 or arms, a pair, 15 shaped to receive the rear

end of the last 5. A screw 16 engages in the opening 14 and has an annular flange 17 to engage over the upper surfaces of the legs 10 and a head 18 for manipulation of the screw so as to tighten or untighten the engagement of the flange 17 with the legs 10.

It is thought that the construction, operation, manipulation and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what is claimed as new is:

1. A device for holding a toe stretching shoe 25 last in a shoe, comprising a member including a substantially horizontal part extending above the top of the shoe and above the rear portion of the last, and a depending part at the rear end of the horizontal part extending into the shoe 30 and engaging the heel part thereof, a member depending from the horizontal part and slidably arranged thereon and removably contacting the rear portion of the last, and means for fastening the last mentioned member in adjusted position 35 on the horizontal part.

2. A device for use with a toe stretching shoe last, comprising a substantially U-shaped member providing a front bight part and a pair of rearwardly extending limbs, the ends of the limbs 40 being bent downwardly and having their rear edges shaped to engage the heel of the shoe, a flat member contacting the under edges of the limbs and having a depending part for engaging the rear end of the last, the last mentioned member having a threaded hole therein, a screw engaging the hole and passing through the space between the limbs, said screw having a head having its lower end resting on the upper edges of the limbs, whereby releasing the screw, the last 50 engaging member can be adjusted longitudinally on the limbs and then by tightening the screw, said member is locked in adjusted position.

3. A device for holding a toe stretching shoe last in a shoe, comprising a substantially U- 55

shaped member providing a front bight part and a pair of rearwardly extending limbs, the ends of the limbs extending downwardly for entering and contacting the heel portion of the shoe, a member having a part slidably engaging the horizontal portions of the limbs, and a depending

part engaging the rear part of the last and means for fastening said member in adjusted position on the horizontal parts of the limbs, the depending part of said member including a pair of spaced limbs.

SAMUEL SAMUEL.
